Primary Examiner — Stacia Cadmus*(74) Attorney, Agent, or Firm* — Dennis A. DeBoo**(57) CLAIM**

The ornamental design for a license plate sports mask, as shown and described.

DESCRIPTION

FIG. 1 is a front perspective view of a license plate sports mask, showing my new design;

FIG. 2 is a front elevational view thereof;

FIG. 3 is a right side elevational view thereof, the left side being a mirror image;

FIG. 4 is a top view thereof;

FIG. 5 is a bottom view thereof;

FIG. 6 is a rear elevational view thereof;

FIG. 7 is a front perspective view thereof, the broken lines depict a license plate frame environmental structure for illustrative purposes only and form no part of the claimed design; and,

FIG. 8 is a rear perspective view thereof.
